OFF SPOT PIN DETECTING AND SWEEP CONTROL MECHANISM FOR BOWLING PIN SPOTTING MACHINES

Gottfried J. Schmidt, Pearl River, N. Y., assignor to Bowling Patents Management Corporation, a corporation of New York

Application April 8, 1944, Serial No. 530,097

6 Claims. (Cl. 273—43)

1

This invention relates to bowling pin setting machines and more particularly to off spot pin detecting and pin removal control mechanism for use with such machines.

The mechanism constituting the present invention relates generally to devices for use with machines of the general type shown in my co-pending application, Serial No. 399,815, filed June 26, 1941 for Pin Setting Apparatus for Bowling Alleys, which has matured into Patent No. 2,346,189, granted April 11, 1944, and Nejedly Patent No. 2,298,718, issued October 13, 1942, for Bowling Pin Setting Machine Control Mechanism, although if desired this mechanism can be employed with other machines designed for the same purpose.

In a machine of the type shown in the above referred to Nejedly patent, there is provided a pin setter mounted for movement to and from a pin setting and resetting position on a bowling alley. Mounted upon the setter are a plurality of pin resetting units preferably so constructed and arranged that each unit is individually movable laterally with respect to standing pins on the alley so that when the setter is lowered to the above referred to position, each standing pin, whether on or off spot will be lifted and reset in proper position on the alley. The range of action of each pin resetter unit is defined by its peripheral extent, so that if a unit is circular its operative extent is controlled by its diameter.

It is well known that as a result of play, pins may be moved by a ball thrown along the alley or "walk" as a result of ball or falling pin movement. Usually the distance of pin travel is relatively small so that each resetter unit on the setter can perform its designed functions. However, at relatively infrequent intervals it may happen that a standing pin will move or be moved beyond the range of operation of a resetter unit, and hence cannot be lifted and reset. In such case the longitudinal axis of a standing pin may be located beyond the limits of the periphery of a resetter unit or two pins may be positioned to engage a single unit. This means that although the setter can be lowered towards the alley after the throwing of a ball and the resetter units made operative to lift standing pins, nevertheless because of the presence of one or more pins so far removed from pin lifting position with respect to a resetter unit or units, the downward travel of the setter to its lifting and resetting position will be prevented. Hence, when it is raised pins which should have been lifted will remain standing on the alley. Under such conditions the sweep, which is operative to remove

2

deadwood or fallen pins from the alley at this time, will remove these standing pins, prevent proper playing of the game, and possibly result in an infraction of the rules of the game, such for instance as those established by the American Bowling Congress. It is, therefore, an object of my invention to prevent the removal of pins remaining standing on an alley after a ball has been thrown until all balls of a frame have been thrown, and it is desired to set a new frame of pins.

It is an added object of my invention to provide mechanism which will prevent removal of standing pins regardless of their positions on the playing bed of an alley after the throwing of a ball unless each standing pin has been properly lifted and is supported above the alley during the operation of the fallen pin or deadwood removing mechanism.

20 It is a further object of my invention to insure against infraction of established rules of play, if for any reason after the throwing of the first ball of a frame, pins have walked or been moved beyond the range of operativeness of the pin resetting members on the pin setter and cannot be picked up thereby for sweeping and resetting.

It is a further object of my invention to provide means for incapacitating the pin removing mechanism which is normally operative to remove fallen pins or deadwood from the alley and gutters unless pins remaining standing on the alley after the throwing of the first ball of a frame are located within the range of action of the pin handling mechanism provided for lifting and resetting the same before and after the operation of the pin removing mechanism.

It is a further object of my invention to provide means for preventing operation of the pin removing mechanism, such as a sweep, normally operative to remove fallen pins or deadwood from an alley after the throwing of a ball, especially the first ball of a game, if for any reason the pin handling device which sets and resets pins is prevented from moving to its pin lifting and resetting position.

It is a further object of my invention to provide selective control mechanism for controlling the operation of the pin removing mechanism or sweep after the throwing of a ball, and especially 50 the first ball of a frame, if the pin handling device which sets and resets pins is prevented from moving to its pin lifting and resetting position, by reason of a pin moving beyond the range of operation of a lifting unit, or two pins being positioned to be engaged by the same lifting unit.

It is a further object of my invention to pro-

vide selective control mechanism for controlling the operation of the pin removing mechanism or sweep after the throwing of a ball, especially the first ball of a frame, if for any reason some of the pins cannot be lifted and the normal play of a game is prevented as a result thereof.

With these and other objects not specifically mentioned in view, the invention consists in certain combinations and constructions which will be hereinafter fully described, and then set forth in the claims hereunto appended.

In the accompanying drawings which form a part of this specification, and in which like characters of reference indicate the same or like parts:

Figure 1 is a side elevation of a machine embodying the invention;

Figure 2 is a partial side elevation of a detail showing a part of the pin setter and the resetter units carried thereby;

Figure 3 is a diagrammatic partial front elevation, partly in section, showing the sweep control mechanism and a suitable electric circuit for controlling the operation of same;

Figure 4 is a partial front elevation, partly diagrammatic, showing a part of the pin setter and certain electric contacts;

Figure 5 is a diagrammatic view showing part of the sweep control mechanism; and

Figure 6 is a plan view of the cam controlling the operation of the setter in its movement to and from the alley.

In the preferred embodiment of my invention, selected for purposes of illustration, as shown in the several figures, there is provided a pin removing mechanism such as a sweep R, which is mounted for movement to and from and back and forth along the alley at proper times after the throwing of a ball for removing deadwood or fallen pins or unwanted standing pins from the alley. In general, this mechanism may be of the type shown in Rundell Patent No. 2,250,503, granted July 29, 1941. Since it is desirable to prevent a player from throwing a ball until the sweep R has been returned to inoperative position, it is preferred to provide a guard G of the type shown in the Rundell patent which cooperates with the sweep R and is located adjacent the alley during its operation and the setting and resetting of pins.

The sweep and guard mechanism is operated from a motor M (Figure 1). Mounted upon motor shaft 12 is a sprocket 14 which is connected to the driving sprocket 13 loosely mounted on shaft 14 by means of a chain 15. Fixed to shaft 14 is a sprocket 16 which is driven at suitable intervals by sprocket 13 and a clutch C which will be described more fully hereinafter. Sprocket 16, by means of chain 19 running on sprocket 17, drives a shaft 18 to which sprocket 17 is secured. Sprocket 20 on shaft 18 drives a chain 23 which runs on and drives sprocket 21 fast to shaft 22. A spur pinion 24 mounted on shaft 22 meshes with a spur gear 25 on cam shaft 26 on which are mounted cams 27, 28 and 102 (Figure 3), which through the drive of the spur gears, above referred to, control the movement of the pin and ball remover or sweep R and guard G and setter T.

As disclosed in the Rundell patent, a lever 29 pivotally mounted on a pin 30 suitably supported in the frame of the machine has attached to one end a cable 31 which is trained over a pulley 32 mounted on the machine frame and at its other end the cable is attached to a lever 33 fixed on

5 a shaft 34 rotatably supported in brackets 35 suitably fixed to the frame of the machine (as shown in Figure 1).

When a frame of pins has been set upon the bed of an alley, as shown in full lines in Figure 1, in readiness for play and the first ball is thrown down the alley, it lands in the pit adjacent thereto, and rests on pit elevator E and depresses a control bar 10 which closes a switch 16 of any suitable conventional type thereby making a series circuit including conductors 14, 15 and solenoid S. The energization of solenoid S causes the clutch C, which may be of the well known Bliss type, to effect a driving engagement between sprocket 13 and shaft 14 which through the several driving connections heretofore described causes cam shaft 26 to rotate through one revolution.

Upon movement of cam 27, cam follower 36 on lever 29 which bears against the cam surface 27, causes lever 29 to swing about pin 30 and feed cable 31 over the pulley 32 sufficiently to allow lever 33 and shaft 34 to rock and locate the sweep R and guard G adjacent the alley. Referring to Figure 1, it will be seen that in the form disclosed, guard G and sweep R are preferably mounted on a framework composed of substantially parallel front and rear arms 37 and 38, respectively. Front arms 37 fixed to shaft 34, are connected by means of links 40 to rear arms 38, which are pivotally mounted in brackets 39 supported on the frame of the machine. In this manner provision is made for giving the frame a parallel horizontal motion as it descends upon the alley.

35 The frame is lowered under the control of cam 27 by gravity. One end of a cable 41 is attached approximately midway to a cross bar 70 connecting the front arms 37, which cable is trained over pulleys 42 mounted on the frame of the machine and secured to a weight 43 of suitable proportions to act as a counterbalance for the frame.

40 Guard G referred to hereinabove, is mounted on bar 70 fixed to the free ends of arms 37. The guard which may consist of a board or other suitable ball deflecting member, moves down into a position adjacent the alley and remains stationary during the operation of the sweep R. In this manner the sweep, and the pin setter, which is responsible for setting and resetting pins are protected against carelessly or inadvertently thrown balls and damage to the machine is prevented inasmuch as a ball cannot pass beyond the guard until all pin removal and setting or resetting operations have been effected and the frame returned to inactive position above the alley.

45 Sweep R is operated by means of a cam follower 44 on cam lever 45 pivotally mounted on shaft 47 suitably supported in the frame of the machine. Cam follower 44 engages a track in cam 28 loosely mounted on shaft 26 (see Figures 1 and 3) and secured to a driven clutch member 110 by screws 115 or other suitable means. A clutch operating member, such as a bolt 112 slidably mounted in clutch member 110 is pressed by spring 114 into engagement with an aperture 111 in driving clutch member 104 fixed by key 105 to shaft 26. By means of this arrangement, cam 28 is normally given one complete revolution per cycle, unless as described hereinbelow, the cam is disconnected by withdrawal of bolt 112 from aperture 111. Cam 28 and driven clutch member 110 are maintained in proper operative relation to clutch member 104 by means of collar 108 fixed to shaft 26 by screw 106.

Lever 45 is also provided with a gear segment 46, which meshes with a pinion 48 on shaft 49 and spur gear 51 mounted on shaft 52. A sprocket 53 also mounted on shaft 52 is rigidly connected to gear 51, and a chain 55 transfers the drive therefrom to a sprocket 54 loosely mounted on shaft 34 supported in brackets 35 and to a sprocket 56 loosely mounted on shaft 34 and rigidly connected to sprocket 54. Extending rearwardly from cross bar 70 which supports guard G, are arms 71 in which is journalled a shaft 60 having fixed at one end a double sprocket 57, 59, and at the other end a sprocket 61. Trained over sprocket 57 is a chain 58 which transfers rotary movement from sprocket 56 to shaft 60. Idler sprockets 64, 65 mounted on studs fixed in the free ends of arms 38 support chains 62 extending between sprockets 59 and 64, and between sprockets 61 and 65 respectively. Sweep R is secured to support chains 62 for movement longitudinally back and forth along the alley in a manner similar to that shown and described in the above referred to Rundell Patent 2,250,503.

It is evident, therefore, that sweep R, in the illustration, is so mounted that in the normal operation of the machine, the sweep R and guard G are moved into operative position relative to the alley after each ball of a frame has been thrown along the alley. In the normal operation of the machine after the first ball, any standing pins are lifted by the units U on the setter which dwells above the alley during the travel of the sweep along the alley to move fallen pins or deadwood into the pit at the end of the alley. After the throwing of the last ball allotted per frame, all deadwood, as well as any pins standing on the alley are moved by sweep R into the pit, after which the sweep returns to inactive position adjacent the guard, a new frame of pins is set, and the guard and sweep are moved to inoperative position, as shown in full lines in Figure 1, in order that play may continue.

The mechanism constituting the present invention is designed primarily to prevent removal of any standing pin or pins remaining on the alley if for any reason the individual pin resetting units U on setter T cannot engage a pin normally positioned to be gripped and lifted thereby. For instance, in the usual game of ten-pins, two balls are allotted for each frame. The 50 resetter units U on setter T are so spaced in triangular arrangement, that after the throwing of the first ball, when setter T is lowered, any standing pin has located thereabove a re-setter unit U adapted to grip and lift the same when the setter is raised and held above the alley during the operation of the guard and sweep.

The preferred design of units U is the same as that shown in the Nejedly patent referred to hereinabove. Each unit U may be likened generally to a truncated cone or inverted funnel mounted on a support plate 97 for independent lateral and vertical movement. In this way as setter T is lowered, the handle end of a standing pin bears against the inclined side 144 of a unit and causes the whole unit to shift and align itself therewith. Since pins have a tendency to "walk" as a result of being hit by a ball or falling pins, it is common knowledge that all pins remaining standing after a ball has been thrown may not occupy their original on-center or on-spot positions. The above arrangement insures that standing on and/or off spot pins will be lifted, and reset after sweeping in substantially the positions each occupied prior to lifting.

While the units U are so designed and spaced on plate 97 of setter T, that under all normal conditions on or off spot pins will be lifted after the throwing of the first ball so that sweep R may 5 remove fallen pins, it may happen on relatively rare occasions that a standing pin may walk or be moved by a ball or falling pins beyond the limits of operation of a unit U positioned on setter T to engage such pin, or as a result of the 10 travel of the ball two pins may be positioned in close adjacency one to the other. Hence, when setter T is lowered, such unit U cannot operate to grip and lift the pin. An example of this condition is illustrated diagrammatically in Figure 3 15 where a pin P has walked to a position between two units U and cannot be gripped by either. Also the downward movement of the setter T to its lowermost position or to setting-resetting position is prevented because of the engagement by 20 plate 97 thereof with the head of one or more standing pins. A similar condition would obtain if two pins were located in close adjacency, as mentioned above. In such case no standing pin can be lifted and in the operation of setter control cam 102 the setter is raised leaving all pins standing on the alley subject to removal by the sweep R. Since there is another ball or balls to be 25 thrown, it is obvious that this condition interferes radically with further play of that frame. Therefore, mechanism is provided for incapacitating 30 the sweep to prevent removal of these pins.

The construction and operation of setter or 35 table T may be generally the same as that shown in the Nejedly patent aforementioned. The setter may consist of a frame provided with a hollow supporting shaft 390, mounted for turning in slide blocks 391 supported in slides 3 formed in side uprights 6 located at opposite sides of the machine for movement to and from the playing surface of the alley for setting and resetting pins thereon. As shown in the Nejedly patent, setter devices (not shown) and resetter units U are mounted on the setter for setting and resetting pins, respectively.

In order to accomplish the desired movement of the table T, to and from the pin supporting surface of the alley, there may be provided, as in the above referred to Nejedly patent, a gear segment 200 formed on lever 202 loosely mounted on shaft 19 and provided with a cam follower 201 engaging cam 102, which segment engages a pinion 204 fixed to a shaft 206 mounted in side frames 2. Also fixed to shaft 206 is a sprocket 208 about which is trained sprocket chain 210 running on sprocket 212 fixed to shaft 214 supported in bearings 216 secured to machine frame uprights 6. Mounted on shaft 214 adjacent uprights 6 are drum pulleys 218 upon which are wound cables 9 attached to slides 3. Rotation of cam 45 102, therefore, results in the winding and unwinding of cables 9 and the raising and lowering of table T to upper pin receiving and lower pin lifting positions. A suitable counterweight (not shown) may be used to balance the table T.

Each resetter unit U carries a fluid operated switch device 320 and said devices close contacts in the several units U in a series circuit 560 (Figures 3 and 4) whenever the setter T is lowered after the throwing of the first ball and a strike 50 has been made in which case all pins are knocked down. All switch contacts 320 in the units U also close in the conditions above described, as where a pin standing on the playing surface has walked beyond the limits of operation of a unit U but 55 70 75 the removal of such pin or pins is precluded by

incapacitating the sweep, as described hereinabove. In order to prevent the delivery of a new set of pins to the alley by suitable mechanism, such as disclosed in my above referred to patent No. 2,346,189, it will be seen that even though all switches 320 are closed by operation of the fluid lines, nevertheless switches 344, 348 and 364, 366 remain open and the circuit to the pin feeding control mechanism (not shown) remains open (Figure 3). Operating fluid, such as suction, is conducted by conduits 76, 76' through shaft 390 to suitable pipes (not shown) connected to each of the units U. The mechanism for controlling the operation of units U and switch devices 320 can be the same as shown in the above referred to Nejedly patent and since this mechanism does not form a specific part of the present invention, further description and showing are omitted in the interest of brevity.

As mentioned hereinabove, upon each movement of setter T to pin lifting position after the first ball of a frame is thrown, series circuit 560 is closed through the resetter units U, unless upon normal full movement of the setter T, as shown in Figure 4, standing pins hold at least one of the switches open and prevent this circuit from being made. In the case where the setter is prevented from moving to its full lower position because a standing pin has walked beyond the range of action of a given unit U, so that the setter T occupies the position shown in full lines in Figure 3, switches 320 are closed by operation of the fluid control mechanism (not shown), but switches 344, 348 and 364, 366 are open and delivery of a new set of pins to the alley is prevented.

In order to overcome conditions such as noted above, control mechanism is provided to maintain proper continued operation of the machine, and insure the normal operation of sweep R after each ball of a frame, and incapacitate the sweep when the conditions described hereinabove occur.

A suitable control is shown in Figures 3 and 4. This control includes a movable member, such as disc 122 and suitable associated control elements, 45 and a ratchet relay of suitable conventional design, shown diagrammatically in Figure 3 and designated F, and the other circuits and associated elements shown in Figure 3.

Fixed to shaft 26 is a gear 116 which drives gear 118 secured to shaft 120 and held in operative position relative to frame 2 by collar 121. Also secured to shaft 120 is a disc 122 having mounted thereon substantially 180° apart, contact plates 124, 126. As shown in Figures 3 and 5, the contact plates 124, 126 are located on opposite sides of disc 122. The relation between gears 116, 118 is such that shaft 120 makes one-half rotation for every complete revolution of shaft 26. When for example, in playing tenpins, as a result of the first ball of a frame thrown, a pin has walked or been moved out of the range of operation of a unit U, or when two pins have become relocated in close adjacency, as setter T moves downwardly, plate 97 engages the head end or ends of such pins and further downward movement of the setter to its lowermost or pin lifting and setting position is prevented. At this intermediate position, switch member 154 mounted on support 343 (Figure 3) engages switch member 156 fixed to support 346. Support 343 is attached to bracket 356 clamped to shaft 390. A contact plate 328, also suitably fixed to bracket 356, carries spaced contacts 332 which are adapted to engage with contacts 329, 362 mounted on

5 support plate 334 secured to setter T. When setter T occupies a position shown in Figure 4, contacts 332 engage with contacts 329, 362 and complete series circuit 560. Cables 9, supporting the setter T for raising and lowering, will continue to be paid out, as the setter is held up by a standing pin or pins. Supports 343 and 346, shown broken away in Figures 3 and 4, illustrate diagrammatically the relative positions of the several switches.

10 The relative positions of disc 122 and contact plates 124, 126 carried thereby, contacts 128, 130 and support 343 are such that switch members 154, 156 are normally momentarily in engagement and separated again as setter T is moved in its normal operation downwardly to pin lifting and resetting position before contacts 124, 128 or 126, 130 become engaged as the result of rotation of disc 122. When, however, a pin has walked too far off-spot and occupies a position such as shown in Figure 3, downward movement of setter T to pin lifting position is prevented because bottom plate 97 engages the head of a standing pin. In this condition switch members 154, 156 come into and remain in engagement until the setter T is again moved upwardly. For this reason contacts 124, 126 on disc 122 are mounted for engagement by stationary contacts 128, 130 at some suitable angle, say 30° from zero, in the cycle.

20 As shown in Figure 3, ratchet relay F, which may be of any suitable conventional commercial type, such as series S-125, made by Guardian Electric Manufacturing Company, Chicago, Illinois, consists of an electromagnet 326 acting on an armature 330 pivoted at 331 which is normally held against stop 328' by spring 328. A spring urged pawl 330' of conventional design is pivotally mounted on the end of armature 330 and engages a ratchet 332' on shaft 337 suitably supported in the ratchet relay. Cam 336 is also mounted on shaft 337. Contact arm 341 is provided with a nose portion 339 which rests against cam 336 and is held thereagainst by spring 341'. Contact point 351 on the end of arm 341 alternately engages points 353 and 355 as cam 336 rotates. Ratchet 332' has twice as many teeth as the number of high points on cam 336 in order to effect the desired alternate engagement between contact point 351 and points 353, 355. It follows, therefore, that on successive operations of electromagnet 326, contact point 351 is alternately brought in contact with points 353 and 355.

25 Contact 353 is connected to switch 130 which is closed by segment 126 on one side of disc 122. Contact 355 is connected to switch 128, closed by segment 124 on the opposite side of disc 122. Therefore, as long as arm 341 does not move, the circuit from arm 341 to wire 304, connected to the other side of switches 130 and 128, is closed only once during each full revolution of disc 122 or once for each two-ball frame. In the position shown, with contact point 351 engaging point 353, switch 130 is closed by segment 126, this operation occurring during the first ball cycle only.

30 In case the first ball of a frame has knocked a pin P far enough off-center without toppling it, to engage the bottom plate 97 of the pin setter T, as shown in Figure 3, relay magnet 312 will be energized through switch 130, contact points 353—351 and contacts 156 and 154. Relay magnet 312 closes contact 313, thereby energizing solenoid 142. Connected to the plunger of solenoid 142 is one end of lever 132, the other end of which

is adapted to be moved against the action of spring 140 into the position shown in dotted lines in Figure 3 to position nose 148 on lever 132 in the path of movement of shoulder 150a of slide bolt 112 and thereby cause disengagement of clutch slide bolt 112 in the manner described, to discontinue operation of cam 28 and hence prevent operation of sweep R. In a case such as this, continued rotation of cam 102 results in raising setter T to its dwell position above the alley leaving on and/or off-spot pins standing on the alley bed. Any deadwood or fallen pins can be removed manually, if necessary, after which play can be resumed as usual.

If a standing pin is moved to the position shown in Figure 3 by the second ball of a frame, relay 312 is not energized. This time switch 128 is closed by segment 124, but contact 355 is open.

If all pins are knocked down by the first ball of a frame (a strike), all switches 320 are closed by the fluid operating means, as disclosed in the above referred to Nejedly Patent No. 2,298,718, when the pin setter T reaches its lowest position. Consequently magnet 326 of the ratchet relay is energized through switches 320, contact spring 344 engaging point 348 and spring 364 engaging point 366. Ratchet 332' is moved one tooth and point 351 breaks away from point 353 and engages point 355. Spring 154 is not in engagement with point 156 while switch 139 is closed by segment 126, so relay 312 is not energized during this cycle. Through suitable mechanism (not shown) which can be of the type shown in my above referred to Patent No. 2,346,189, ten new pins are set on the alley during the remaining part of the cycle.

The cycle following this strike cycle must again be a first ball cycle. Assume a pin is knocked off-center in this first ball cycle beyond the range of cones 144. As switch 130 is closed during the previous (strike) cycle, switch 128 is going to close this time and, with arm 341 in lower position, the circuit to relay 312 will now be completed through points 351—355 and switch 128. In other words switch 128 has now become the first ball switch until another strike comes along, advancing ratchet 332' another tooth and returning arm 341 to upper position.

In Figure 3 a suitable circuit for energizing solenoid 312 and effecting the operation of clutch operating lever 132 is disclosed. Power lines L₁ and L₂ are connected to the high side of transformer 307. From the low side of transformer 307, power is conducted by conductor 304 to contacts 124 or 126, thence through contacts 351 and 355 or through contacts 351 and 353, through contact lever 341, contacts 156 and 154, conductor 308, through the coil of solenoid 312 and conductor 310 back to the low side of transformer 307. When this circuit is made, solenoid 312 is energized and closes switch 313. This results in establishing a circuit including power line L₁, conductor 316, the coil of solenoid 142, now closed switch 313, conductor 314 and power line L₂, which energizes solenoid 142, and as described hereinabove, clutch lever 132 is moved to locate nose 148 in position to engage shoulder 150a of slide bolt 112 and interrupt the operation of cam 28, thereby preventing the operation of sweep R. Adjusting screws 136, mounted in projections 137 on a bracket 139, suitably attached to frame 2, are adjusted in desired positions to limit the extent of movement of lever 132.

The invention above described may be varied in construction within the scope of the claims, for

the particular device, selected to illustrate the invention, is but one of many possible concrete embodiments of the same. It is not, therefore, to be restricted to the precise details of the structure shown and described.

What is claimed is:

1. In a bowling pin setting machine, an elevator, means for moving said elevator to and from the playing surface of an alley to set pins on-spot and reset pins on or off-spot in substantially triangular playing arrangement thereon, means operative after each ball has been thrown for effecting movement of said elevator to and from said surface, a supporting plate carried by said elevator, said plate being provided with a plurality of openings, pin removing mechanism, means for operating said mechanism to remove pins from said surface after the throwing of each ball, means for determining the presence of standing pins on said surface after the throwing of the first ball of a frame comprising spaced pin handling units positioned on said plate and located in substantially triangular arrangement above said openings, and means operative if any pins standing on said surface after the first ball is thrown have moved off-spot and beyond the limits of operation of a unit between said openings in said plate, whereby said plate engages the head of a standing pin for incapacitating said mechanism to prevent removal of said standing pin from said alley surface.

2. In a bowling pin setting machine, an elevator, a plurality of spaced pin resetters on said elevator, means for moving said elevator to and from the playing surface of an alley after the throwing of a ball to locate said resetters in position to grip and lift any pin standing on said alley after the throwing of a ball, a pin sweep, mechanism operative after the throwing of a ball for moving said sweep back and forth along said alley, an electric circuit connecting said resetters, means normally operative to close said circuit unless said means is incapacitated by a pin standing on said alley as a result of the first ball of a frame thrown, and means for preventing operation of said mechanism if a pin remaining standing on said alley after the first ball prevents movement of said elevator to said position, said mechanism including a shaft, a cam loosely mounted on said shaft, a driving member, a clutch normally coupling said member to said cam, and means for declutching said member from said cam when said sweep is to be rendered inactive.

3. In a bowling pin setting machine, a sweep for removing fallen and unwanted pins from a bowling alley, driving means for operating said sweep after each ball of a frame thrown, a control device for said driving means, a movable control member, means moving said control member in timed relation with said driving means, an electric circuit connecting said device and member, spaced contacts on opposite sides of said member, complementary contacts located in said circuit for alternate engagement by said contacts on said member, and means operable after the throwing of the first ball of a frame and knocking down of all pins on said alley for operating said device to cause one or the other of said contacts on said movable member to engage one of said complementary contacts and be connected in said circuit.

4. In a bowling pin setting machine, a sweep for removing fallen and unwanted pins from a bowling alley, driving means for operating said

11

sweep after each ball of a frame thrown, a control device for said driving means, a movable control member, means moving said control member in timed relation with said driving means, an electric circuit connecting said device and member, spaced contacts on opposite sides of said member, complementary contacts located in said circuit for alternate engagement by said contacts on said member, means operable after the throwing of the first ball of a frame and knocking down of all pins on said alley for operating said device to cause one or the other of said contacts on said movable member to engage one of said complementary contacts and be connected in said circuit, and means for incapacitating said driving means whenever said circuit is completed.

5. In a bowling pin setting machine for use with a bowling alley having a pin supporting surface, a pin handling device movable to and from said surface, mechanism for removing pins from said surface, means for operating said mechanism after the throwing of each ball of a frame along said surface, means for moving said device to a pin lifting position above said surface, and control means operative during the continued operation of said machine if said device is prevented from moving to said pin lifting position for incapacitating said mechanism, said control means comprising a rotatable disc, an electric circuit, control contacts carried by said disc, a ratchet relay connected in said circuit, a contact member operated by said relay to make said circuit through one of said contacts on said disc, and

means operative upon completion of said circuit to incapacitate said mechanism.

6. In a bowling pin setting machine for use with a bowling alley having a pin supporting surface, a pin handling device movable to and from said surface, mechanism for removing pins from said surface, means for operating said mechanism after the throwing of each ball of a frame along said surface, means for moving said device to a pin lifting position above said surface, and control means operative during the continued operation of said machine if said device is prevented from moving to said pin lifting position for incapacitating said mechanism, said control means comprising a rotatable disc, an electric circuit, control contacts carried by said disc, a ratchet relay connected in said circuit, a contact member operated by said relay to make said circuit through one of said contacts on said disc, means operative upon completion of said circuit to incapacitate said mechanism, and control elements operative whenever said circuit remains broken for continuing the operation of said mechanism.

GOTTFRIED J. SCHMIDT.
